UNITED STATES PATENT OFFICE.

HOWARD N. WEDDLE, OF DINUBA, CALIFORNIA.

SAW-SUPPORTING MEANS.

1,145,284.

Specification of Letters Patent.

Patented July 6, 1915.

Application filed March 17, 1913. Serial No. 754,952.

To all whom it may concern:

Be it known that I, HOWARD N. WEDDLE, citizen of the United States, residing at Dinuba, in the county of Tulare and State 5 of California, have invented certain new and useful Improvements in Saw-Supporting Means, of which the following is a specification.

My invention relates to improvements in 10 saws and broadly includes novel supporting means therefor, whereby the same may be held in an upright position when not in use.

An object of this invention is to provide 15 an improved saw embodying novel supporting means such as will hold the same in an upright position (when desired) and being so arranged that it will prevent lateral tilting thereof, ordinarily due to jarring.

Another object is to construct a device 20 of this nature wherein the saw blade and supporting means are preferably formed integral, consequently reducing cost of manufacture, and at the same time greatly 25 increasing the durability of the device.

A further object is to arrange the supporting means in such a manner that the lateral tilting of the saw is prevented, the saw 30 end being cut at right angles to the longitudinal axis of the saw and disposed adjacent the terminus of its longitudinal sides.

A still further object of the present device is to provide novel saw supporting 35 means so arranged as to support the same in an upright position yet disposed in such manner that it will not impede operation thereof in any way.

With the above and other objects in view, 40 my invention relates to such details of construction, combination and arrangement of parts as will be hereinafter more fully described and specifically pointed out in the appended claims.

In describing my invention in detail, reference 45 will be had to the accompanying drawings, wherein like characters denote like or corresponding parts throughout the several views, and in which—

Figure 1, is a side elevation of an ordinary saw illustrating the improved supporting means formed integral therewith, Fig. 2, is an edge view of the saw showing 50 the same being disposed in an upright position, and Fig. 3, is an enlarged view of

one end of the saw illustrating the construction of the supporting means more clearly.

In the accompanying drawings wherein is illustrated the preferred embodiment of my invention, I have illustrated the same 60 in conjunction with a saw of the ordinary type. This is merely shown to display the application of my invention, consequently the latter may be employed in connection with saws of other types when so desired. 65

The saw illustrated in the drawing consists of a body or blade portion 10 which is carried by a handle portion 11 of the usual form, fastening means 12 being employed for attachment thereto. In providing my 70 invention in connection with a saw of this character, the end thereof is first cut away at right angles to the longitudinal axis of the blade in order to provide a substantial 75 level plane for accommodating the supporting means, the supporting means in this position being more capable of supporting the saw in an upright position and preventing lateral tilting thereof.

My invention consists more essentially in 80 the provision of extended prongs 13 which are sharpened at their outer extremities as illustrated in order to prevent slipping when supporting the saw in an upright position. One prong is preferably disposed adjacent 85 the terminus of the smooth longitudinal edge of the saw blade while the other is disposed in proximity to the inner edge of the teeth formed on the other longitudinal edge. This method of disposition provides 90 a more efficient support in consistent with the efficient operation of the saw. The supporting means being disposed in this manner will prevent lateral tilting of the saw to an appreciable extent consequently greatly 95 adding to the utility thereof.

In Fig. 2, I have illustrated the saw in conjunction with a support 14 showing the former in an upright position, such as assumed when provided with the improved 100 supporting means disclosed.

The prongs 13 are preferably cast integral with the saw blade in order to reduce cost of manufacture, however, it will be further recognized that this will also greatly add to 105 the durability of the device.

The greatest of stress is laid upon the specific disposition of the prong in view of

the fact that lateral tilting of the saw is prevented due to the prongs being spaced from the longitudinal axis thereof.

The advantages resultant from the use of my invention, will be readily comprehended by those conversant with the crude and unsatisfactory devices, heretofore employed in this art.

Such changes as are permissible by the subjoined claims may be resorted to without departing from the spirit of my invention.

Having thus fully described my invention, what I claim as new and desire to secure by Letters Patent is:—

1. In combination with a saw having the usual flexible blade, spurs on the free end of the blade for engagement with the floor

to retain the blade from displacement, when the saw is inclined against a vertical support.

2. A hand saw comprising a blade having a handle at one end and having integral spaced apart spurs projecting longitudinally from the end of the blade opposite the handle, said spurs being adapted to retain the lower end of the blade from slipping, and to retain the blade from edge-wise tilting when the saw is inclined against a vertical support.

In testimony whereof I affix my signature in presence of two witnesses.

HOWARD N. WEDDLE.
